UNITED STATES PATENT OFFICE

167,833

AUTOMOBILE ORNAMENT OR THE LIKE

Robert H. Hieger, Detroit, Mich.

Application September 11, 1950, Serial No. 12,146

Term of patent 7 years

(Cl. D14—18)

To all whom it may concern:

Be it known that I, Robert H. Hieger, a citizen of the United States and a resident of Detroit, Wayne County, Michigan, have invented a new, original, and ornamental Design for an Automobile Ornament or the like, of which the following is a specification, reference being had to the accompanying drawing, forming part hereof.

In the drawing:

Fig. 1 is a view in elevation of an automobile ornament or the like showing my new design;

Fig. 2 is a cross sectional view of the same, taken on the line 2—2 of Fig. 1; and

Fig. 3 is a view in side elevation of the same.

Fig. 4 is a vertical median sectional view of the design of Fig. 1, looking in the same direction as in Fig. 3.

The dotted lines in Figs. 1 and 2 are for illustrative purposes only, and they indicate the outline of a medallion-holding bezel, or of a medallion, insertable into or received by the ornament.

I claim:

The ornamental design for an automobile ornament or the like, substantially as shown and described.

ROBERT H. HIEGER.
